UNITED STATES PATENT OFFICE.

JUSTUS R. KINNEY, OF BOSTON, MASSACHUSETTS.

AIR-MOTOR.

1,088,155.

Specification of Letters Patent.

Patented Feb. 24, 1914.

Application filed February 10, 1913. Serial No. 747,579.

To all whom it may concern:

Be it known that I, JUSTUS R. KINNEY, a citizen of the United States of America, and a resident of Boston, in the county of Suffolk and State of Massachusetts, have invented certain new and useful Improvements in Air-Motors, of which the following is a specification.

The invention relates to air motors and particularly to that type of motors in which a piston is reciprocated by a supply of compressed air intermittently admitted to the piston chamber, the main object of the present invention being to provide a single valve mechanism for controlling the admission of the motive agent and providing subsequently for the exhaust thereof, said valve mechanism being positively operated at predetermined times by the reciprocatory movement of the piston.

The invention consists in controlling both the admission and the exhaust of the motive agent by a single valve mechanism.

The invention further consists in a tubular valve member provided with two sets of ports one of which communicates at all times with the piston chamber, while the other set is adapted to communicate alternately with the inlet and outlet as the piston approaches the end of its stroke in opposite directions.

The invention further consists in a friction device to retain said valve member in a normal stationary position until positively moved by the reciprocation of the piston.

The invention further consists in providing the piston with a cylindrical member movable therewith adapted to receive the end of the tubular valve which is provided with a shoulder adapted to engage a shoulder on said piston to move said valve in unison with said piston a limited distance in one direction, while the end of said cylindrical extension is adapted to engage the end of said tubular valve to move it in unison with said piston a limited distance in the opposite direction.

The invention consists further in certain novel features of construction and arrangement of parts which will be fully understood by reference to the description of the drawings and to the claims hereinafter given.

Of the drawings: Figure 1 represents a vertical section of a motor embodying the

features of the present invention. Fig. 2 represents a transverse section of the same, the cutting plane being on line 2—2 on Fig. 1. Fig. 3 represents an enlarged vertical section of a portion of the same, the cutting plane being on line 3—3 on Fig. 5. Fig. 4 represents a horizontal section on line 4—4 on Fig. 3, and Fig. 5 represents a horizontal section on line 5—5 on Fig. 3.

Similar characters designate like parts throughout the several figures of the drawings.

In the drawings, 10 represents the base of a casing 11. This casing 11 is provided at opposite ends with removable plates 12, each provided with a bearing 13 in which is adapted to rotate the crank shaft 14. The shaft 14 has formed therein a plurality of cranks 15 each connected by a link 16 with a piston 17. Each piston 17 is adapted to reciprocate in a cylinder 18 threaded or otherwise secured to the casing 11. Each piston 17 is provided with an annular flexible packing 19 retained against an end of the piston 17 by means of an annular member 20 secured to the piston 17 by means of screws 21. At the upper end of each of these cylinders 18 is secured a casing 22 the upper end of which is closed by means of a cap 23. This casing 22 is provided with a chamber 24 having an inlet port 25 extending therefrom and communicating with a passage 26 through which compressed air or some other motive agent is adapted to be admitted to the chambers 24. A cylindrical passage 27 extends from each chamber 24 to the interior of one of the cylinders 18. Fitted to the passage 27 is a tubular valve member 28 having cut into its periphery an annular groove 29 from which extends a plurality of ports 30 communicating with the interior of said tubular member. This tubular member 28 is also provided with a plurality of radial ports 31 which are always uncovered and communicate with the interior of the cylinder 18. The tubular member 28 is shown in the drawings as being formed in two parts, the body portion 28 and a supplemental tubular part 32 of reduced diameter threaded to the body portion. It is obvious, however, that the tubular valve 28—32 may be made integral if desired. The lower end of the supplemental part 32 is provided with an outwardly extending flange 33 and above

100
105
110

this flange 33 surrounding the supplemental part 32 is a buffer spring 34. This supplemental part 32 extends into a cylindrical extension 35 secured to the piston 17, as clearly indicated in Fig. 3 of the drawings, the lower end of this extension 33 being closed by a plug 36 on the inner end of which rests a yielding pad 37. The supplemental part 32 is also provided with a plurality of ports 38 adapted to communicate with the interior of the cylinder 18 during the reciprocation of the piston 17.

Threaded or otherwise secured to the upper end of the tubular valve member 28 is a stem 39 provided with a flange 40 between which and the end of the tubular member 28 is interposed a washer 41. Surrounding the stem 39 is a washer 42 of yielding material, this washer 42 resting on an annular shoulder 43 formed in the wall of the chamber 24. Superimposed upon the washer 42 are two semi-annular friction members 44 each having a peripheral groove 45 therein adapted to receive a split annular spring 46. This spring forces the friction members 44 into contact with the stem 39 so that the tubular valve member 28 is retained in its normal position until positively moved by the reciprocation of the piston 17. It is apparent from an inspection of the drawings that the supplemental reduced part 32 is telescopically connected with the piston 17 so that said piston may reciprocate throughout the greater portion of its stroke without effecting any movement of the valve member 28, but while at the extreme end of the stroke of said piston in either direction a positive movement of the valve 28 will be insured. In the position shown in Fig. 3 of the drawings the compressed air or other motive agent from the source of supply is admitted through the passage 25 to the chamber 24. This motive agent will then enter through the ports 30 and pass downwardly through the interior of the tubular member 28 and then through the ports 31 into the interior of the cylinder 18, against the end of the piston 17 to impart downward movement thereto. During the first part of this downward movement the friction members 44 acting upon the stem 39 will retain the valve 28 in the position shown in Fig. 3, permitting the continued admission of the motive agent to the interior of the cylinder 18. When, however, the piston 17 approaches the end of its stroke in the downward direction, a shoulder upon the member 20 will come into contact with the spring buffer 34 and positively move the valve 28 downwardly, overcoming the friction of the members 44 upon the stem 39. This operation will move the valve 28 into the position shown in Fig. 2 of the drawings with the washer 41 in contact with the lower end wall of the chamber 24.

The motive agent entering the chamber 24 will act upon the flange 40 and tend to retain the valve to its seat. In this position the ports 30 will be in the same plane with the exhaust port 47. The air in the cylinder 18 may then be exhausted therefrom through the ports 31, the interior of the tubular member 28, the ports 30, and the exhaust outlet 47. The friction members 44 acting upon the stem 39 will then retain the valve 28 in the position shown in Fig. 2 until the piston 17 approaches the end of its stroke in the opposite direction. Just before the end of the stroke in this direction the pad 37 upon the plug 36 will contact with the lower end of the supplemental part 32 and will move the valve 28 upwardly again into the position shown in Fig. 3.

While three cylinders are shown in the drawings, it is obvious that a greater number may be used if desired, and the cranks for the various pistons will be equally distributed about the axis of the crank shaft 14. The casing 11 is provided with another series of openings 48, which are normally closed by caps 49. These may be removed to gain access to the interior of the crank casing when desired. These openings are the same as those into which the cylinders 18 are threaded, and when it is desired to construct the engine with the cylinders 18 parallel with the base 10 the caps 49 may be removed and the cylinders inserted in these openings 48, the caps 49 then being screwed into the other openings 50.

This makes a very simple construction of air motor which is particularly adapted for use in connection with self-starters for motor cars. The construction and operation of the valve mechanism is greatly simplified by telescopically connecting it with the piston so that during a portion of the stroke of the piston the valve will be held stationary while a positive movement is imparted thereto at the end of the stroke in each direction, thus permitting the motive agent to be alternately admitted to the piston chamber and exhausted therefrom through the same tubular valve.

It is believed that the construction and operation of the invention will be fully understood from the foregoing description.

Having thus described my invention, I claim:

1. In a device of the class described, the combination of crank mechanism; a cylinder; a reciprocating piston therein adapted to operate said crank mechanism; and means controlled by said piston for admitting a motive agent to the closed end of said cylinder and subsequently exhausting the same therefrom.

2. In a device of the class described, the combination of crank mechanism; a cylin-

der; a reciprocating piston therein adapted to operate said crank mechanism; and telescopic means controlled by said piston for admitting a motive agent to the closed end of said cylinder and subsequently exhausting the same therefrom.

3. In a device of the class described, the combination of crank mechanism; a cylinder; a reciprocating piston therein adapted to operate said crank mechanism; a valve for controlling the admission of the motive agent to the closed end of said cylinder; and means on said piston for operating said valve.

10 4. In a device of the class described, the combination of crank mechanism; a cylinder; a reciprocating piston therein adapted to operate said crank mechanism; a valve for controlling the admission of the motive 20 agent to the closed end of said cylinder; and means on said piston for operating said valve at the end of the stroke of said piston in each direction.

5. In a device of the class described, the combination of a cylinder; a reciprocating piston therein; a valve for controlling the admission of the motive agent to said cylinder; means on said piston for operating said valve at the end of the stroke of said piston 30 in each direction; and frictional means for retaining said valve in open position until positively closed by the movement of said piston.

6. In a device of the class described, the combination of a cylinder; a reciprocating piston therein; a valve for controlling the admission of the motive agent to said cylinder; means on said piston for operating said valve at the end of the stroke of said piston 40 in each direction; members in frictional contact with the stem of said valve to retain it in open position until positively closed by the movement of said piston; and a spring clip surrounding said members.

45 7. In a device of the class described, the combination of crank mechanism; a cylinder closed at one end; a reciprocating piston therein adapted to operate said crank mechanism; a valve for controlling the admission 50 of the motive agent to the closed end of said cylinder; means coacting therewith to retain it in open position until positively moved; and a telescopic connection between said valve and said piston adapted to positively close said valve at the end of the working stroke of said piston.

8. In a device of the class described, the combination of a cylinder; a reciprocating piston therein; a valve for controlling the admission of the motive agent to said cylinder; means coacting therewith to retain it in open position until positively moved; a closed cylindrical extension on said piston; a tubular member secured to said valve and 60 provided with ports, said member extending

into said extension and having a lateral shoulder thereon; means on said piston with which said shoulder engages in the movement of said piston to effect a closing of said valve.

9. In a device of the class described, the combination of a cylinder; a reciprocating piston therein; a valve for controlling the admission of the motive agent to said cylinder; means for coacting therewith to retain it in open position until positively moved; a closed cylindrical extension on said piston; a tubular member secured to said valve and provided with ports, said member extending 70 into said extension and having a lateral shoulder thereon; means on said piston with which said shoulder engages in the movement of said piston to effect a closing of said valve; and a buffer spring interposed between said engaging means and said shoulder.

10. In a device of the class described, the combination of a cylinder; a reciprocating piston therein; a chambered member secured to the end of said cylinder and having an inlet thereto for the motive agent; a valve 90 in said chamber provided with a tubular stem extending longitudinally of said cylinder, said stem being provided with a plurality of ports and an engaging shoulder; means on said piston for engaging said shoulder to operate said valve at predetermined times; and frictional means for retaining said valve in open position until positively closed by the movement of said piston.

11. In a device of the class described, the combination of a cylinder; a reciprocating piston therein; a chambered member secured to the end of said cylinder and having an inlet thereto for the motive agent; a valve 105 in said chamber provided with a tubular stem extending longitudinally of said cylinder, said stem being provided with a plurality of ports and an engaging shoulder; means on said piston for engaging said shoulder to operate said valve at predetermined times; frictional means for retaining said valve in open position until positively closed by the movement of said piston; and means on said piston for positively opening 110 said valve at the end of a predetermined movement of said piston.

12. In a device of the class described, the combination of a cylinder; a reciprocating piston therein; a chambered member secured to the end of said cylinder and having an inlet thereto for the motive agent; a valve in said chamber provided with a tubular stem extending longitudinally of said cylinder, said stem being provided with an engaging shoulder; means on said piston for engaging said shoulder to operate said valve at predetermined times, frictional means for retaining said valve in open position until positively closed by the movement of said 120 piston.

- piston; means on said piston for positively opening said valve at the end of a predetermined movement of said piston; an exhaust port in said chambered member; and 5 two sets of ports in said tubular stem one set of which is adapted to register with said exhaust port at a predetermined position of said piston to permit exhaust from said cylinder.
- 10 13. In a device of the class described, the combination of a cylinder; a reciprocating piston therein; a chambered member secured to the end of said cylinder and having an inlet and outlet therein; a valve in said 15 chamber provided with a tubular stem having two sets of ports therein, one of which sets is always in communication with the interior of said cylinder, while the other set is adapted to alternately communicate with 20 said exhaust port and the inlet chamber; means connected to said piston effecting movements of said valve in opposite directions at predetermined times; and means for preventing movement of said valve except 25 when positively operated by the reciprocation of said piston.
14. In a device of the class described, the combination of a cylinder; a reciprocating piston therein; a chambered member secured 30 to the end of said cylinder and having an inlet and outlet therein; a valve in said chamber provided with a tubular stem having two sets of ports therein, one of which sets is always in communication with the interior of said cylinder while the other set 35 is adapted to alternately communicate with said exhaust port and the inlet chamber; a cylindrical extension on said piston into which the end of said valve stem extends and 40 is adapted to reciprocate, said extension being provided with a closed end adapted to move said valve in one direction a limited distance; and means on said piston adapted to engage with said stem and move said
- valve in the opposite direction a limited 45 distance.
15. In a device of the class described, the combination of a cylinder; a reciprocating piston therein; a chambered member secured to the end of said cylinder and having an 50 inlet and outlet therein; a valve in said chamber provided with a tubular stem having two sets of ports therein, one of which sets is always in communication with the interior of said cylinder, while the other set 55 is adapted to alternately communicate with said exhaust port and the inlet chamber; a cylindrical extension on said piston into which the end of said valve stem extends and is adapted to reciprocate, said extension 60 being provided with a closed end adapted to move said valve in one direction a limited distance; means on said piston adapted to engage said stem and move said valve in the opposite direction a limited distance; and means preventing the movement of said valve except when positively operated by the reciprocation of said piston.
16. In a device of the class described, the combination of crank mechanism; a cylinder 70 closed at one end; a reciprocating piston therein adapted to operate said crank mechanism; a chambered member secured to the end of said cylinder having an inlet and an outlet therein; and a single device reciprocable in said chambered member and operable by the movement of said piston for closing the outlet and opening the inlet at 75 the end of the stroke of said piston in one direction and closing the inlet and opening the outlet at the end of the stroke of the piston in the opposite direction.

Signed by me at 4 Post Office Sq., Boston, Mass., this 5th day of February, 1913.

JUSTUS R. KINNEY.
